ALARM CLOCK

Claude Vuille, Fribourg, Switzerland, assignor to
Derby S.A., Canton, Switzerland

Filed 27, 1964, Ser. No. 78,809

Term of patent 14 years

(Cl. D42—7)

FIG. 1

FIG. 2

FIG. 3

FIG. 4

FIG. 5

FIG. 1 is a front elevational view of an alarm clock showing my new design;

FIG. 2 is a side elevational view thereof;

FIG. 3 is a rear elevational view thereof;

FIG. 4 is a view similar to FIG. 2 but showing the back in its open, supporting position; and

FIG. 5 is a rear elevational view thereof. The side not shown is substantially a mirror image of the side shown.

I claim:

The ornamental design for an alarm clock, substantially as shown and described.
